UNITED STATES PATENT OFFICE.

OSCAR TEMPLE, OF JEFFERSON CITY, MISSOURI.

BICYCLE-PUMP.

SPECIFICATION forming part of Letters Patent No. 597,226, dated January 11, 1898.

Application filed February 6, 1897. Serial No. 622,315. (No model.)

To all whom it may concern:

Be it known that I, OSCAR TEMPLE, a citizen of the United States, residing at Jefferson City, in the county of Cole and State of Missouri, have invented certain new and useful Improvements in Bicycle-Pumps; and I do hereby declare the following to be a full, clear, and exact description of the invention, such as will enable others skilled in the art to which it appertains to make and use the same.

My invention relates to improvements in bicycle-pumps, and has for its object to provide a telescopic foot-pump the parts of which are designed to fold in close compass in order that the device may be handily carried by the rider.

To this end my invention consists in certain novel constructions, combinations, and arrangements of parts, as will be hereinafter described and claimed.

In the accompanying drawings, Figure 1 is a central vertical sectional view showing the pump-cylinders extended and the piston up. Fig. 2 is a similar view, but shows the piston down to the bottom of the inner cylinder. Fig. 3 shows the pump closed or telescoped and the foot-rest folded. Fig. 4 shows a detail view of the piston-rod and folding handles. Fig. 5 is a top view of the foot-band.

Referring to the drawings, the letter A designates a base or outside cylinder provided at its lower end with supporting-legs b and a central nozzle c for the eduction of air, to which a hose or tube is to be applied. A metal band d is suitably pivoted to one of the legs b and is adapted to be swung under between the legs when not employed. By pressing on this band with the foot the pump may be held firmly to the ground.

A cylinder E fits within the outside cylinder, the upper edge of the outer cylinder and the lower edge of the inner cylinder being flanged to prevent said cylinders from parting, a packing f being interposed to form a tight joint. The upper end of the inner cylinder has an opening through which a piston-rod g passes and holes h at the sides for admission of air. The piston-rod carries on its inner end a piston-head g', and in practice

this rod will be of such length that when the 50 piston-head is at its lowermost position it will close and serve as a head for the lower end of the inner cylinder.

The end of the piston-rod which projects through the upper head of the inner cylinder 55 is provided with an eye h, to which a handle is attached. This handle comprises two right-angled bars i j, an arm i' j' of each bar having an eye by which it is pivoted to the piston-rod by means of a pin or otherwise. The 60 hole in the upper head of the inner cylinder is just large enough to permit the piston-rod to work loosely through it. The lower pivoted ends i' j' of the handle bridge across this opening and serve as stop-shoulders to prevent the piston from dropping out of the inner cylinders. By this construction it will be seen that when the pump is not in use the handles may be turned in opposite directions, so that the horizontal portions thereof will 70 lie close alongside the outer wall of the pump in vertical disposition.

It will be seen that the act of forcing the piston down first forces the air from the movable inner cylinder E until when the piston 75 arrives at the lower end of the inner cylinder the air is entirely expelled therefrom. At this point the ends of the arms i' j' abut on the upper end of the inner cylinder and the piston arrives at the lower end of the latter. 80 The piston then serves as a head for said inner cylinder, which, when forced through the outer cylinder, expels the air from the latter.

By the construction herein described I provide a bicycle foot-pump which is of small 85 compass and can be carried handily by the rider, and yet is adapted to furnish a copious supply of air by which a tire may be quickly inflated.

Having thus described my invention, what 90 I claim as new, and desire to secure by Letters Patent, is—

1. A bicycle-pump comprising a cylinder, a piston working therein, a piston-rod attached by one end to the piston and the upper end thereof extending through the upper head of said cylinder, and a handle comprising two right-angled bars each having an arm

pivoted to the said upper end of the piston-rod and adapted to be turned down with their horizontal portions in vertical position parallel with the side wall of the piston, substantially as described.

5 2. A bicycle-pump comprising a cylinder provided at its lower end with supporting-legs and an air-education nozzle, a piston in said cylinders, and a foot-clamp pivoted to one of

10 said legs and adapted to fold in the space between the legs, substantially as described.

In testimony whereof I have signed this specification in the presence of two subscribing witnesses.

OSCAR TEMPLE.
